SIGNAL CONTROL APPARATUS

Arthur E. Dodd, Edgewood, Pa., assignor to The
Union Switch & Signal Company, Swissvale,
Pa., a corporation of Pennsylvania

Application July 30, 1942, Serial No. 452,904

6 Claims. (Cl. 175—320)

My invention relates to signal control apparatus, and particularly to apparatus for flashing danger signals at highway-railroad crossings to warn users of the highway of the approach of a train upon the railway.

In many installations of highway crossing signals employing flashing lights, the lamps are energized by alternating current except when a failure in the alternating current supply occurs, in which event the lamps are connected to a source of direct current, such as a storage battery, through the medium of a power transfer relay. The relays employed for flashing the lights in such installations are usually of the direct current type, and are therefore normally energized from the storage battery which serves as the standby source of power for the lights.

If the flasher relays in such installations can be made to operate from either alternating or direct current, a savings can be effected in the relay contacts required, and the wiring can be simplified, and one object of my present invention is to provide means for accomplishing this desirable result.

Another object of my invention is to provide means whereby a flasher relay can be made to operate on either alternating or direct current without changing the physical construction of the relay.

The flasher relays commonly employed for flashing lights in control apparatus embodying my invention normally include a pair of windings and an armature which is caused to oscillate by alternately short circuiting the relay windings by contacts operated by said armature, and according to my invention I accomplish the aforementioned objects by interposing in the control circuit for the flasher relay between the control contacts and each winding one or more rectifiers so arranged that the windings will always be supplied with direct current of the same polarity regardless of whether the control circuit is energized from a source of direct or alternating current. Since the current which flows through the control contact with this arrangement is normally alternating current, this contact may be utilized to perform the added function of flashing the lights of a highway crossing signal, with the result that for the same total number of relay contacts, the lamp capacity of the flasher relay will be increased or for a given lamp capacity one set of contacts can be eliminated. This arrangement also has the advantage that it is only necessary to run two control wires from the power source to the flasher relay in-

stead of the four wires that have heretofore usually been required, which results in a reduction in the number of contacts required on the relays normally employed to control the control circuits.

I shall describe three forms of signal control apparatus embodying my invention, and shall then point out the novel features thereof in claims.

10 In the accompanying drawings, Fig. 1 is a diagrammatic view showing one form of signal control apparatus embodying my invention. Figs. 2 and 3 are diagrammatic views showing modified forms of the apparatus illustrated in Fig. 1, and also embodying my invention.

Similar reference characters refer to similar parts in all three views.

Referring first to Fig. 1, the reference characters 1 and 1a designate the track rails of a stretch 20 of railway track over which traffic normally moves in both directions, and which stretch is intersected by a highway H. The track rails 1 and 1a are divided by means of insulated joints 2 to form two track sections A—B and B—C which extend in opposite directions from the highway. The one track section A—B is provided with a track circuit comprising a track battery 3 connected across the rails at one end of the section and the one magnet 4 of an interlocking relay IR connected across the rails at the other end of the section, while the other track section B—C is provided with a similar track circuit comprising a track battery 3 connected across the rails at one end of the section, and 35 the other magnet 5 of the interlocking relay IR connected across the rails at the opposite end of the section.

The interlocking relay IR may be of any of the well-known types, such for example, as the relay described and claimed in Letters Patent of the United States No. 1,799,629, granted to William K. Lockhart and Thomas J. O'Meara on April 7, 1931, and as here shown is provided with a back contact 6 which is controlled by magnet 4 and with a back contact 7 which is controlled by magnet 5. The construction of the relay is such that if either magnet becomes deenergized before the other magnet, the armature controlled by the magnet first to become deenergized will drop all of the way to its full released position and will operate a mechanical interlocking device which will prevent the other armature from dropping past its mid stroke position as long as the magnet 50 first to become deenergized subsequently remains

deenergized, even though the first magnet to become deenergized subsequently picks up.

It will be seen, therefore, that when a train moving from left to right traverses the stretch of track shown in the drawings, contact 6 of relay IR will become closed upon the entrance of the train into section A—B and will subsequently remain closed until the train clears this section, but that under these conditions contact 7 will remain open even though magnet 5 will become deenergized while the train is traversing section B—C. In a similar manner, when a train traverses the stretch of track shown in the drawings in the opposite direction, contact 7 will become closed when the train enters section B—C and will subsequently remain closed until the train clears this section, but contact 6 will remain open in spite of the fact that magnet 4 will become deenergized while the train is passing through section A—B.

Located on opposite sides of the railway adjacent the intersection of the railway and the highway are two highway crossing signals S1 and S2 the function of which is to warn users of the highway when a train is approaching the highway in either direction. These signals as here shown are of the well-known type comprising two lamps which are adapted to be alternately flashed to simulate the effect of a swinging red lantern, the lamps of the signal S1 being designated by the reference characters L1 and LL1, and the lamps of the signal S2 being designated by the reference characters L2 and LL2.

For the purpose of flashing the lamps when a train is approaching the intersection a flasher relay FR controlled by the interlocking relay IR is provided. This relay is of well-known construction and comprises three magnetizable cores 8, 9 and 10 connected together at their upper ends by a backstrap 11 and provided at their lower ends with enlarged pole pieces 8a, 9a and 10a, respectively. The core 8 carries an energizing winding 12 and the core 10 carries a similar energizing winding 13, while the core 9 carries a plurality of closed conductors here shown as washers 14, the number of which serves to determine the time characteristics of the relay, as will be explained more fully hereinafter.

A magnetizable armature 15 is pivotally supported directly below the pole piece 9a for swinging movement toward one or the other of the pole pieces 8a and 10a, and is operatively connected with two contact fingers 16 and 17. When armature 15 is swung toward pole piece 10a, as shown in the drawings, contact finger 16 engages a fixed contact member 16a to close a contact 16—16a and contact finger 17 engages a fixed contact member 17a to close a contact 17—17a. When armature 15 is swung toward pole piece 8a, however, contact finger 16 then engages a fixed contact member 16b to close a contact 16—16b and contact finger 17 engages a fixed contact member 17b to close a contact 17—17b.

In accordance with my present invention the windings 12 and 13 are connected in series in an energizing circuit which includes two full wave rectifiers, one of which R1 has its output terminals connected directly with winding 12 and the other of which R2 has its output terminals connected directly with winding 13. This circuit also includes a pair of wires 18 and 19 and the two contacts 6 and 7 of interlocking relay IR in multiple, and is arranged to be supplied with alternating current from the secondary winding 20 of a transformer T, or with direct current from a battery D, according as the front contacts 21—21a

and 22—22a or the back contacts 21—21b and 22—22b of a power transfer relay PTR are closed. The primary winding 23 of transformer T is constantly connected with the terminals BX and CX of a suitable source of alternating current not shown, and the power transfer relay PTR is constantly connected to the secondary winding 20 of transformer T. It follows, therefore, that the energizing circuit for the windings 12 and 13 of relay FR will be supplied with alternating current from the secondary winding 20 of transformer T except in the event of failure in the alternating current supply in which case the resultant deenergization of relay PTR will cause this circuit to be supplied with direct current from the battery D. The battery D is preferably of the storage type, and is maintained in its fully energized condition under normal conditions by energy supplied to it from a second secondary winding 24 of transformer T through a rectifier R3.

The energizing circuit for the windings 12 and 13 of relay FR further includes the contacts 16—16a and 16—16b of relay FR so arranged that when the contact 16—16a is closed, it will short circuit the input terminals of rectifier R2, and that, when the contact 16—16b is closed, it will short circuit the input terminals of rectifier R1. The terminals of the windings 12 and 13 are connected with the output terminals of the rectifiers R1 and R2 in such manner that the flux induced in core 9 when the winding 12 is energized will traverse this core in the opposite direction to that induced in core 9 when the winding 13 is energized.

With the energizing circuit for relay FR arranged in the manner just described, when this circuit becomes closed at either contact 6 or contact 7 of relay IR, if armature 15 occupies the position shown so that contact 16—16a is closed, current will be supplied to winding 12 through this contact, but winding 13 will remain deenergized due to the short circuit provided by this contact. The energization of winding 12 will set up a flux in core 8 which will cause armature 15 to swing toward pole piece 8a. This motion of the armature will open contacts 16—16a and 17—17a and close contacts 16—16b and 17—17b. The closing of contact 16—16b will short circuit winding 12, and the field set up in core 8 by this winding will commence to decay. Due, however, to the snubbing effect of the short circuited winding and to the washers 14 on core 9, this decay will be comparatively slow. The opening of contact 16—16a in the meantime will have removed the short circuit from winding 13 with the result that current will now be supplied to winding 12 through contact 16—16b. The growth of the field set up in core 10 by this latter winding will be comparatively slow due to the washers 14, but after an interval of time the torque exerted on armature 15 by this flux will overbalance the torque exerted on armature 15 by the decaying flux in core 8, and when this happens, armature 15 will swing toward pole piece 10a. This motion will first open contacts 16—16b and 17—17b and will then close contacts 16—16a and 17—17a. The field of winding 12 will then slowly build up and the field of winding 13 will slowly decay, this decay being retarded by the self-inductance of winding 13 and the washers 14. Eventually the torque exerted by the flux in core 10 will not be sufficient to hold armature 15 and the armature will then again swing toward pole piece 8a. It will therefore be apparent that armature 15 will be swung to and

from or oscillated as long as either contact 6 or contact 7 of interlocking relay IR remains closed, and it will also be apparent that a time interval will elapse between successive armature movements. It will further be apparent that since the flux set up by both windings 12 and 13 traverses the common core 9, and since the rate at which the flux builds up and decays in this core depends upon the number of washers 14 on this core, the time interval which elapses between successive armature movements may be readily varied by varying the number of washers 14 on core 9. The operation of relay FR will be the same regardless of whether the energizing circuit is supplied with alternating current from the secondary winding 20 of transformer T or with direct current from the battery D.

The lamps L1 and LL1 of signal S1 are connected in series between the line wires 18 and 19, but when the contact 16-16a is closed, the lamp LL1 is short circuited by this contact and when the contact 16-16b is closed, the lamp L1 is short circuited by this contact. It will be apparent, therefore, that when the relay FR is operating, the lamps L1 and LL1 will be alternately flashed, and that if the relay should fail to operate for any reason, one or the other of these lamps will always be lighted.

In a similar manner the lamps L2 and LL2 of signal S2 are connected in series between the line wires 18 and 19, but when the contact 17-17a is closed, the lamp LL2 is short circuited by this contact, and when the contact 17-17b is closed, the lamp L2 is short circuited by this contact. It follows, therefore, that when relay FR is operating, these lamps will be flashed in unison with the lamps L1 and LL1, and that if relay FR fails to operate for any reason when its energizing circuit becomes closed, one or the other of the lamps L2 and LL2 will always be lighted.

The operation of the apparatus as a whole will be apparent from an inspection of the drawings and from the foregoing description without further detailed description.

As was pointed out hereinbefore, it is desirable in the interest of economy to normally energize the lamps of highway crossing signals by alternating current since it can be obtained at a lower cost than direct current, and it should be particularly pointed out that with the apparatus arranged in the manner just described I am able to accomplish this result and to control the flashing of the lights with a standard direct current flasher relay over a single pair of wires extending from the source of power to the relay location. This effects a savings of at least two wires over the arrangements heretofore generally employed in which the relay is normally energized from direct current and the lamps from alternating current.

It should also be pointed out that since the rectifiers R2 and R1 are located between the control contacts 16-16a and 16-16b and the associated windings 12 and 13 of relay FR, I am able to utilize the contacts 16-16a and 16-16b to perform the added function of flashing one or more pairs of lights with the result that for the same total number of relay contacts, the lamp capacity of the flasher relay is increased, or for a given lamp capacity one set of lamp contacts can be eliminated.

Referring now to Fig. 2, as here illustrated, the full wave rectifier R1 shown associated with the winding 12 in Fig. 1 has been replaced by two half wave rectifiers R4 and R5, and the full

wave rectifier R2 shown associated with the winding 13 in Fig. 1 has been replaced by two half wave rectifiers R6 and R7. The half wave rectifiers R5 and R7 are connected in the energizing circuit in series with the windings 12 and 13, respectively, and serve to supply these windings with half wave energy of the proper polarity when the energizing circuit is being supplied with alternating current, while the rectifiers R4 and R6 are shunted across the windings 12 and 13 and help to smooth out the pulsations in the half wave energy supplied to these windings through the rectifiers R5 and R7.

This arrangement has the advantage that it reduces the number of rectifier units required, but it is open to the disadvantage that the relay windings 12 and 13 are required to have a lower resistance than is the case when the full wave rectifiers R1 and R2 are employed. It is also subject to the disadvantage that it is necessary in order to cause the relay FR to operate in the event of failure in the alternating current supply that the battery D be connected with the energizing circuit in a manner to cause the wires 18 and 19 to have a particular relative polarity.

It should be pointed out that it is at present the common practice to shunt a half wave rectifier across the windings 12 and 13 for the purpose of suppressing radio interference, and when this is the case, the only additional rectifiers required with the arrangement shown in Fig. 2 are the rectifiers R5 and R7.

The operation of the apparatus as a whole when arranged as shown in Fig. 2 is similar to the operation of the apparatus when arranged as shown in Fig. 1, and will be apparent from an inspection of the drawings without further detailed description.

Referring now to Fig. 3, as here shown, the windings 12 and 13 are center tapped, and have their center taps connected with the line wires 19 and 18, respectively. Two half wave rectifiers R8 and R9 connected in series and poled in the same direction insofar as their series connection is concerned are shunted across the winding 12 and have their common connection connected to the contact finger 16, and two similar half wave rectifiers R10 and R11 connected in series and poled in the same direction insofar as their series connection is concerned are shunted across the winding 13 and have their common connection connected to the contact finger 16. The windings 12 and 13 are so constructed that each half of these windings has the same resistance as the total resistance of these windings in Figs. 2 and 3. The remainder of the apparatus shown in Fig. 3 is similar to the corresponding portion of the apparatus shown in Figs. 1 and 2.

With the apparatus arranged as shown in Fig. 3, when the energizing circuit is supplied with alternating current, the windings 12 and 13 will become alternately short circuited to cause the relay to oscillate in the same manner as in the preceding views. When either winding is not short circuited, the two halves of the winding will be alternately energized on alternate half cycles of the alternating current and the associated rectifiers are so poled that the flux set up in the associated core when either half is energized will traverse the core in the same direction, whereby the core will be supplied with energy on each half of the alternating current cycle, thereby accomplishing full wave rectification with fewer rectifier units than in Fig. 1.

With this arrangement it is not necessary that the wires 18 and 19 have a particular relative polarity when the energizing circuit is supplied with direct current, and the cores will be supplied with flux of substantially the same magnitude regardless of whether the energizing circuit is supplied with alternating or direct current.

Although I have herein shown and described only three forms of signal control apparatus embodying my invention, it is understood that various changes and modifications may be made therein within the scope of the appended claims without departing from the spirit and scope of my invention.

Having thus described my invention, what I claim is:

1. In combination, a relay comprising two windings, an armature which is moved to one position or another according as one winding or the other is energized, a first contact closed when said armature occupies its one position and a second contact closed when said armature occupies its other position, a first full wave rectifier having its output terminals connected with said one winding, a second full wave rectifier having its output terminals connected with said other winding, an energizing circuit for said relay including a pair of wires one of which is connected with the one input terminal of the one rectifier and the other of which is connected with the one input terminal of the other rectifier, means connecting the remaining input terminals of said rectifiers together, means for short circuiting said one winding when said first contact is closed, and means for short circuiting said other winding when said other contact is closed, whereby said armature will oscillate when said energizing circuit is supplied with either alternating or direct current.

2. In combination, a relay comprising two windings, an armature which is moved to one position or another according as one winding or the other is energized, an energizing circuit for said windings including said windings connected in series, means including a first contact closed when said armature is moved to said one position for short circuiting said one winding, means including a second contact closed when said armature is moved to said other position for short circuiting said other winding, and two full wave rectifiers one interposed in said circuit between each winding and each contact and each having its output terminals connected with the terminals of the associated winding and its input terminals connected across the associated contact in such manner that the rectifier will be short circuited when the associated contact is closed, whereby said windings will be supplied with direct current of the same polarity regardless of whether said energizing circuit is supplied with direct or alternating current.

3. In combination, a relay comprising two windings, an armature which is moved to one position or another according as one winding or the other is energized, two contacts controlled by said armature and one closed when said armature is moved to said one position and the other closed when said armature is moved to said other position, circuit means for short circuiting said one winding over said one contact and for supplying said other winding with current over

said one contact when said one contact is closed, other circuit means for short circuiting said other winding over said other contact and for supplying said one winding with current over said other contact when said other contact is closed; and rectifier means included in said circuit means between said windings and said contacts to render said relay capable of operation on either direct or alternating current.

4. In combination, a relay comprising two windings, an armature which is moved to one position or another according as one winding or the other is energized, two contacts controlled by said armature and one closed when said armature is moved to said one position and the other closed when said armature is moved to said other position, circuit means for short circuiting said one winding over said one contact and for supplying at least a part of said other winding with current over said one contact when said one contact is closed, other circuit means for short circuiting said other winding over said other contact and for supplying at least a part of said one winding with current over said other contact when said other contact is closed, and rectifier means associated with each winding to render said relay capable of operation on either direct or alternating current.

5. In combination, a relay comprising two windings, an armature which is moved to one position or another according as one winding or the other is energized, two contacts controlled by said armature and one closed when said armature is moved to said one position and the other closed when said armature is moved to said other position, circuit means for short circuiting said one winding over said one contact and for supplying said other winding with current over said one contact when said one contact is closed, other circuit means for short circuiting said other winding over said other contact and for supplying said one winding with current over said other contact when said other contact is closed, two half wave rectifiers one included in each said circuit means between each winding and the contact over which the respective winding is energized, and two other half wave rectifiers one shunted across each winding, said last two mentioned rectifiers each being oppositely poled with respect to the other rectifier associated with the same winding.

6. In combination, a relay comprising two center tapped windings, an armature which is moved to one position or another according as one winding or the other is energized, two contacts controlled by said armature and one closed when said armature is moved to said one position and the other closed when said armature is moved to said other position, two half wave rectifiers connected in series across one winding, two other half wave rectifiers connected in series across the other winding, a pair of wires connected respectively with the center taps of said windings, said wires being at times supplied with alternating current and at other times with direct current, a third wire connecting the common connections of said half wave rectifier together, and means connecting said one contact between said third wire and the one circuit wire and said other contact between said third wire and the other circuit wire.

ARTHUR E. DODD.
